(57) **CLAIM**

The ornamental design for a mount for firearm, as shown and described.

DESCRIPTION

FIG. 1 is a top-front-right perspective view of a mount for firearm;

FIG. 2 is a bottom-front-left perspective view thereof;

FIG. 3 is a front view thereof;

FIG. 4 is a rear view thereof;

FIG. 5 is a right-side elevational view thereof;

FIG. 6 is a left-side view thereof;

FIG. 7 is a top view thereof; and,

FIG. 8 is a bottom view thereof.

The broken lines in FIG. 4 depict portions of the mount for firearm that form no part of the claimed design.
